UNITED STATES PATENT OFFICE.

SAMUEL M. KASS, OF PHILADELPHIA, PENNSYLVANIA, ASSIGNOR OF TWO-FIFTHS TO
HARRY E. LATHAM.

PIPE-VISE.

1,236,717.

Specification of Letters Patent. Patented Aug. 14, 1917.

Application filed June 16, 1916. Serial No. 104,100.

To all whom it may concern:

Be it known that I, SAMUEL M. KASS, a citizen of the United States, residing in Philadelphia, county of Philadelphia, and 5 State of Pennsylvania, have invented an Improvement in Pipe-Vises, of which the following description, in connection with the accompanying drawings, is a specification, like characters on the drawings representing 10 like parts.

The invention to be hereinafter described relates to pipe vises of the class in which a chain is employed in connection with a clamping jaw to grip and hold the pipe or 15 similar article while it is being tooled or otherwise treated; and the invention has for its object to provide a device of this character which shall be simple in construction and convenient and effective in operation.

With the above generally-stated object in view, an important feature of the present invention consists in providing a base with a jaw which may be preferably serrated or 25 toothed, and pivotally connecting said jaw at one end with the base and providing a wedge and means for operating it for insinuating the wedge beneath the free end of the jaw to raise the free end of the jaw and 30 the pipe sustained on it into clamping engagement with the chain, one end of which is secured to the base at one side of the pipe and the other end of which is secured to the base at the other side of the pipe. 35 These features of the invention and the preferred form thereof will best be made clear from the following description and accompanying drawings of a good, practical embodiment of the invention.

Referring to the drawings:—The base portion 1 may be formed of suitable material, and in view of the work to be done by the vise, this may preferably be of metal. Rising from the base 1 are the lugs or 45 flanges 2 which may be formed with the base or secured thereto, in parallel separated relation, as shown. These lugs or flanges 2 preferably extend some distance across the base and provide guiding means, as will 50 hereinafter be made clear, for clamping the jaw and, it may be, also for a sliding wedge which operates the jaw.

Pivots mounted between the lugs or flanges 2 is the jaw, which in the present form of the invention, comprises two jaw members 3 pivoted on a suitable supporting pivot or stud 4. Each of the jaw members 3 has a concaved serrated toothed portion 5 which is usual in various forms of jaw pipe vises, and these teeth serve to prevent the 60 pipe from turning while it is being treated.

The jaw members 3 are held in parallel separated relation by any suitable means such as the end cross-piece 6 and by the lugs 7, 7 at the opposite end of the jaw members, said lugs being preferably secured to and between the jaws and formed as the temporary securing means for the clamping chain 8, one end 9 of which is permanently secured to the base 1 between the jaw members by suitable means such as a bolt 10, the construction being such that when a pipe is placed upon the concaved toothed surface of the jaw members, it is engaged by these jaw members at a plurality of points in its 75 length, and between these points the clamping chain 8 is passed over the pipe for holding it seated on the jaw members.

Mounted for sliding movement on the base 1 and preferably inclosed between the lugs or flanges 2, is the block 11 having the wedge portion 12, one for each jaw member, the construction being such that when the block 11 is moved in a direction longitudinally of the jaw members the incline or 85 wedge-shaped end portion 12 will be forced beneath the free ends of the jaw members and cause the jaw members to tightly bind or clamp the pipe between themselves and the chain 8, as will be readily understood.

The form of the wedge or incline portion 12 of the block 11 may be varied, but it is found convenient in the present form of the invention to supplement the incline or wedge portions 12 of the block in their effective action by rounding the free end portions of the jaw members as at 13 so that when the wedge is moved longitudinally of the jaw members its incline portion will readily insinuate itself beneath the free ends 100 of the jaw members and effect the desired clamping action.

The block 11 as hereinbefore noted, is preferably mounted between the lugs or

flanges 2 and guided thereby for its described longitudinal movement, suitable means being provided for imparting such movement, one form of which will now be 5 described.

The lugs or flanges 2 are connected at one end in the illustrated form of the invention by a cross-piece 14 through which is threaded the adjusting device or screw 15, 10 the end 16 of which is rotatably connected to the block 11. The adjusting screw 15 may be operated or turned by the thumb-piece 17, the construction being such that by rotative movement of the adjusting screw 15, the block and force the wedge, carried by it, or formed integral with it, will be moved in a direction longitudinally of the jaw members 3 and serve as they move toward such jaw members to lift the free 15 ends thereof forcibly upward to thereby clamp the pipe between the plurality of points where it is supported by the jaw members and the overlying chain.

It will be understood, of course, that 25 changes may be made in some of the details of the invention without departing from the true scope thereof, as pointed out in the claims, as for instance, the chain securing parts 7 may be either secured to the base 1 or they may be formed upon a block secured to the jaw members 3 near their pivotal mounting on the flanges or lugs 2. Other changes may suggest themselves to 30 those skilled in the art.

35 It may, also, at times, be desirable to reduce the sliding friction between the wedge 12 and the jaw members 13 as the block 11 is adjusted to raise the jaw; and to this end the anti-friction rollers 18 may be mounted 40 either on the wedge in suitable cavities provided therefor, or on the front portions of the jaw members 3, the construction being such that as the wedge is agitated, the anti-friction roller reduces the frictional engagement of these parts.

45 Where the lugs 7 are secured to the jaw members 3 as they would be in the preferred form of construction, it is evident that when the jaw members are lifted by the wedge 50 the chain itself where it is secured to the lug 7, is moved downward with the result that there is a double clamping action, one by the jaw members and the other by the chain, both being effected by the wedge 55 movement.

What is claimed is:—

1. In a pipe vise, the combination of a base, a jaw pivotally connected to the base at one end portion of the jaw and free for 60 movement at its other end in a plane passing transversely of the pivot, a chain secured at one end to the base and adapted to pass over a pipe placed upon the jaw and be detachably connected to the base for movement 65 transversely of the pivotal axis of the jaw,

a sliding block mounted on the base and having a wedge-shaped portion, and means for adjusting the block on the base and the wedge-shaped portion under the free end of the jaw to tilt the jaw about its pivot and 70 clamp the pipe between the chain and jaw.

2. In a pipe vise, the combination of a base having lugs projecting therefrom, a serrated or toothed jaw for supporting a pipe pivotally mounted at one end between said 75 lugs and guided thereby in its pivotal movement, a chain secured to the base at one side of the pipe supported by the pivoted jaw and adapted to be detachably connected to the base at the opposite side of the pipe, 80 a block having the inclined or wedge-shaped end adjacent the free end of the jaw and guided by said lugs for movement in a direction longitudinally of the jaw, and an adjusting device for moving the block and 85 forcing the inclined or wedge-shaped end under the free end of the jaw.

3. In a pipe vise, the combination of a base having separated lugs or flanges extending therefrom, a clamping jaw comprising a plurality of parallel pipe-engaging members pivoted at one end to the base and laterally separated to support a pipe at different points of its length, a chain secured to the base at one side of a pipe seated on 90 the jaw members, means for detachably securing the chain at the opposite side of the pipe, a block guided for movement longitudinally of the jaw members toward and from the pivot of the jaw and having an inclined portion for engaging and moving the free ends of the jaw members about their pivotal connection with the base, and an 95 adjusting device for moving the block.

4. In a pipe vise, the combination of a base 100 having separated lugs or flanges extending therefrom, a clamping jaw comprising a plurality of movable parallel pipe engaging members pivoted at one end to the base and laterally separated to support a pipe at different points of its length, each of said jaw 105 members having rounded free end portions, a chain secured to the base at one side of a pipe seated on the jaw members, means for detachably securing the chain at the opposite side of the pipe, a block guided for movement longitudinally of the jaw members and having an inclined portion for engaging and moving the free ends of the jaw 110 members about their pivotal connection with the base in a plane passing transversely through the jaw pivot, and an adjusting device for moving the block in a straight path.

5. In a pipe vise, the combination of a base having parallel lugs or flanges projecting therefrom, a jaw pivotally mounted at one end between said lugs or flanges and comprising two parallel jaw members guided by said lugs or flanges as the jaw is 115 turned about its pivot, a chain secured to 120 the base in a plane passing transversely through the jaw pivot, and an adjusting device for moving the block in a straight path.

6. In a pipe vise, the combination of a base having parallel lugs or flanges projecting therefrom, a jaw pivotally mounted at one end between said lugs or flanges and comprising two parallel jaw members guided by said lugs or flanges as the jaw is 125 turned about its pivot, a chain secured to 130 the base in a plane passing transversely through the jaw pivot, and an adjusting device for moving the block in a straight path.

the base between the jaw members at one side of a pipe supported on said jaw members, means for detachably securing another part of the chain at the opposite side of the pipe, a block movable longitudinally of the jaw members and having inclined portions for raising the free ends of the jaw members

from the said base and clamping a pipe between the chain and jaw members, and means for sliding the block.

In testimony whereof, I have signed my name to this specification. ¹⁰
